WILLIS A. TRECOTT, OF FAIRPORT, NEW YORK, ASSIGNOR TO THE TRECOTT COMPANY, INC., OF FAIRPORT, NEW YORK, A CORPORATION OF NEW YORK

SORTING APPARATUS

Application filed June 5, 1929. Serial No. 368,625.

This invention relates to sorting apparatus such, for example, as is used for sorting fruit, vegetables, and the like, although it is capable also of other uses. An object of the invention is to provide a generally improved apparatus which is efficient to use, easy to operate, and of flexible character so that it may be adapted to different sorting requirements and used in a number of ways.

Another object of the invention is the provision of an apparatus constructed to sort articles satisfactorily into a number of different grades, and arranged so that all articles may be thoroughly inspected.

Still another object is the provision of a novel form of conveyor for turning the articles carried thereby so that all portions of the articles may be inspected easily and efficiently.

A further object is the provision of sorting apparatus arranged to handle articles gently so as to avoid bruising delicate fruit or breaking fragile articles, and which is economical in floor space occupied and in power required to operate the apparatus.

A still further object is the provision, in sorting apparatus using a belt conveyor, of a satisfactory guard for preventing fraying of the belt at the joint thereof.

To these and other ends the invention resides in certain improvements and combinations of parts, all as will be hereinafter more fully described, the novel features being pointed out in the claims at the end of the specification.

In the drawings:

Fig. 1 is a side elevation of a sorting apparatus constructed in accordance with a preferred embodiment of the invention;

Fig. 2 is a side elevation of the right hand end of the apparatus shown in Fig. 1, drawn on a somewhat larger scale to illustrate additional details;

Fig. 3 is a similar view partly in section of the central portion of the apparatus shown in Fig. 1;

Fig. 4 is a sectional side elevation of the left hand end of the apparatus shown in Fig. 1;

Fig. 5 is a side elevation of the central portion of the apparatus, showing the side opposite to that illustrated in Figs. 1 and 3;

Fig. 6 is a transverse vertical section through the apparatus, taken substantially on the line 6—6 of Fig. 5, showing one of the lateral conveyors in side elevation;

Fig. 7 is a plan of the apparatus;

Fig. 8 is a transverse vertical section taken substantially on the line 8—8 of Fig. 2, with parts omitted;

Fig. 9 is a longitudinal vertical section illustrating a portion of the inspection conveyor and of the grading conveyor onto which the inspection conveyor discharges;

Fig. 10 (sheet 1) is a plan of a fragment of a grading conveyor;

Fig. 11 is a section on the line 11—11 of Fig. 10;

Fig. 12 is a fragmentary plan of a conveyor belt, showing the joint therein and the guard for preventing fraying of the joint, and

Fig. 13 is a section substantially on the line 13—13 of Fig. 12.

Similar reference numerals throughout the several views indicate the same parts.

Although the invention is here disclosed with reference to a preferred embodiment intended for use in sorting or grading apples, it will be understood that the same apparatus with little or no change may be used satisfactorily for sorting oranges, peaches, and other fruits and various forms of vegetables and the like. Furthermore many features of the invention are not limited to sorting apparatus for fruits and vegetables or the like, but may be employed advantageously in connection with sorting apparatus for handling articles of any character.

The apparatus comprises, in general, a series of conveyors, some of which have perforations or openings so that articles of certain selected sizes are separated from other articles of other sizes, other conveyors being arranged to transport the articles to and from the perforated conveyors and to permit inspection of the articles, and still other conveyors being arranged in conveniently accessible positions, so that articles selected as a result of inspection may be placed manually or otherwise upon these other conveyors to be transported to predetermined points.

Referring now to Figs. 1 and 2 of the drawings, there is shown at the receiving end of the apparatus (this being the right hand end when viewed as in Fig. 1) a receiving conveyor 20 which may be, for example, in the form of an endless belt running over rollers 21 and 22, the belt being suitably supported between the rollers. The

articles to be sorted are placed on this receiving conveyor 20 and travel leftwardly thereon until they are discharged on to a short inclined member 23 arranged adjacent to the roller 22. The articles delivered by the conveyor 20 to this inclined member 23 then roll or slide down the incline to a conveyor 24 which preferably has perforations therein so that articles of less than a predetermined size will drop through the conveyor and thus be separated from articles of more than the predetermined size.

This sorting conveyor 24 is inclined slightly upwardly and forwardly, so that articles which do not fall through perforations or become seated therein will not be carried to the discharge end of the conveyor, but will roll back toward the receiving end thereof until each article has either fallen through a perforation or become seated in a perforation. The conveyor may conveniently be constructed of a number of rigid elements flexibly attached to each other, as illustrated particularly in Figs. 10 and 11. As shown in these figures, rings 25 of metal or other rigid material are connected to each other by links 26 which likewise may be of metal, but which form pivotal connections so that the rings 25 may move relatively to each other. The rings 25 of any one conveyor all have the same inside diameter, and preferably concave portions 27 are formed at the outside of each ring, so that these portions 27 on four adjacent rings 25 form another ring of the same inside diameter as the rings 25.

The rings 25 are connected by the links 26 so as to form an endless band or belt of any desired width, which runs over suitable rollers 30 and 31. Since the belt is formed of a series of rigid members (the rings 25) flexibly connected to each other, the guiding rollers 30 and 31 at the ends of this conveyor preferably are not circular but are polygonal in cross section, as is plainly shown in Fig. 2. Each side of the polygon has a length substantially equal to the distance across one of the rigid members 25, so that these rigid members 25 will lie flat on the polygonal faces of the rollers as the belt travels around the rollers, the joints between the rings 25 coming at the corners of the rollers.

When this apparatus is used for apples, for example, those apples having a size less than the diameter of the openings through the ring 25 or between adjacent rings will fall through these openings, and will thus be separated from the apples of larger size which will not fall through the openings but which will be carried on to the discharge end of the conveyor and discharged onto an inclined surface 32 (Fig. 2).

The diameters of the openings in the

rings 25 of the conveyor 24 are so chosen that only the small apples which are worthless for packing will drop through these openings. Such apples may be used satisfactorily in making cider or other products, however, and for that reason they should not be entirely discarded, although they should be separated from the larger and better apples which are to be packed. The small or cider apples after passing through the perforations or openings in the conveyor 24 drop into a chute comprising slats 35 inclined laterally so as to guide the apples out of the path of the lower or return stretch of the conveyor, which chute discharges into a second chute made of slats 36, which conveys the apples back toward the center line of the apparatus and discharges them onto a moving conveyor 37 preferably arranged below the conveyor 24 and substantially along the center line thereof. This conveyor 37 comprises a canvas belt or the like running over pulleys or rollers 38 and 39, the upper stretch of the belt moving leftwardly when viewed as in Figs. 1 and 2 and traveling along the bottom 40 of a trough having side walls 41 to prevent the articles from falling off the sides of the conveyor. The conveyor 37 delivers the apples to an elevator 42 (Figs. 1 and 5) which discharges them into a barrel or other convenient receptacle, or onto another conveyor which may take them to the cider press.

The larger apples, which do not fall through the perforations of the conveyor 24, are discharged as above stated onto the inclined member 32, down which they roll or slide onto what might be termed an inspection conveyor, which transports the apples past an inspection station at which one or more operators or inspectors may be stationed. This inspection conveyor is of novel form and is arranged to turn the articles carried by it so that all sides of such articles will become visible to the inspector. Preferably the conveyor comprises a series of rollers 45, best shown in Figs. 2, 3 and 9, which are arranged substantially parallel to each other with their axes extending crosswise of the apparatus. Links 46 form chains or endless members in which the ends of the rollers 45 are journaled, so that each roller is free to turn about its own axis, but all of them are joined together into a continuous or endless series of rollers to form a sort of belt. This belt formed of the rollers travels over guiding sprockets 47 (Fig. 2) at one end and 48 (Figs. 3 and 9) at the other end, the teeth of the sprockets engaging in openings in the links 46 at the ends of the rollers, so that these rollers are kept properly aligned, and do not tend to become oblique or skewed. The axis of the sprockets 47 is adjustable by means of a screw 49, as shown in Fig. 2, so that the tension on the link

members 46 connecting the rollers to each other may be varied.

The sprockets are driven so that the upper stretch of this inspection conveyor moves leftwardly when viewed as in Figs. 2, 3 and 9. The spaces between adjacent rollers are preferably made somewhat less than the diameter of the perforations in the conveyor 24, so that all articles delivered to the inspection conveyor by the conveyor 24 will remain on the inspection conveyor and will not fall through the spaces between the rollers. Thus the articles are carried along leftwardly by the inspection conveyor, past one or more operators stationed alongside of this conveyor for the purpose of inspecting the articles.

As the rollers move bodily leftwardly from the sprockets 47 toward the sprockets 48, they contact with a strip 50 (Fig. 9) which is stationary, so that the rollers roll along this strip and thus turn in a counter-clockwise direction. This rotation of the rollers causes clockwise rotation of the apples lying in the valleys or crevices between the rollers, so that all sides of the apples are exposed to view during the progress of the conveyor. The inspectors may thus detect any rotten spots or worm holes or other defects in the apples even though such defects might be on the under side of an apple when it was originally placed on the conveyor.

It may be noted here that the separation of the small or cider apples from the others before the other apples reach the inspection conveyor is advantageous, since there is no necessity for inspecting the cider apples, and the number of apples transported by the inspection conveyor is thus reduced. Accordingly, the apples which need to be inspected may be inspected more thoroughly and efficiently, and attention need not be wasted upon the cider apples.

Above the inspection conveyor 45 and conveniently accessible to the operators standing beside this inspection conveyor is a conveyor belt 55 running over pulleys or rollers 56 and 57 (Fig. 1) which are so placed that the belt runs substantially along the center line of the apparatus. Both the upper and lower stretches of this belt are arranged to serve as conveyors for conveying articles in opposite directions, thus effecting economy both in space and in number of parts over the usual practice wherein only one stretch of a belt is used as a conveyor. According to the usual practice, two separate belts would be needed to do the work done by the one belt 55 according to the present invention. This saving of one belt also results in economy of power, since less power is required to operate one belt than two. The upper stretch of the belt 55 is arranged to travel along the bottom of a trough 58 and thus forms a conveyor moving leftwardly when viewed as in Fig. 1, and discharging its articles into

an inclined chute 59 which will be described in greater detail hereafter. This portion of the belt may conveniently be referred to as the conveyor 58. The lower stretch of the belt runs at the bottom of a trough 60, forming a rightwardly moving conveyor which may be conveniently referred to as the conveyor 60. Near the right hand end of this trough 60 there is a deflector 61 (Figs. 1 and 2) arranged to deflect articles carried by the conveyor laterally into an inclined chute 62 down which the articles may roll or slide into any convenient receptacle such as a basket or barrel, not shown.

On each side of the inspection conveyor 45, and conveniently accessible to an operator stationed beside the conveyor, are two chutes 65 (Figs. 2 and 8) which are inclined inwardly and downwardly, discharging into the trough 41 in which the conveyor 37 runs. This conveyor, it will be recalled, conveys the cider apples which are separated out from the others by dropping through the perforations in the conveyor 24.

As the apples delivered to the inspection conveyor 45 by the conveyor 24 travel past the operators stationed alongside this inspection conveyor, and are turned over by rotation of the rollers 45 so that all sides of the apples become visible to the operators, these operators carefully observe the apples and remove certain selected apples by hand from the conveyor. The apples thus removed may be, for example, of three kinds. For instance, the operators may see certain apples which were not small enough to drop through the perforations in the conveyor 20, but which may have certain defects such as rotten spots which make them unfit for packing purposes but suitable for making cider or other products. These apples are picked up by the operators from the conveyor 45 and dropped into the chute 65, from which they are discharged onto the same conveyor 37 which transports the small apples falling through the conveyor 24. Thus this group of apples selected by the inspectors is mingled with the group automatically selected by the conveyor 24, and they are together conveyed to the elevator 42 and into a receptacle or another conveyor, to be used to make cider or other products.

A second kind of apples removed by the operators from the inspection conveyor 45 may be those apples which are unusually large or unusually fine looking. These apples may be placed manually by the operators on the conveyor 58, by which they will be transported to the chute 59 and collected for use as a top layer when packing the apples in barrels or crates. Or, if preferred, these unusually fine apples may be separately packed as an extra fine grade.

A third kind of apples may be removed by the operators from the inspection con-

veyor 45 and may be placed on the conveyor 60. These apples may be those having any characteristics of which it seems desirable or expedient to take note. For instance, it may be thought desirable to separate out a grade of apples slightly better than the cider apples which fall through the conveyor 24, and yet not good enough for ordinary packing. These apples, when placed on the conveyor 60 by the operators, will be discharged through the chute 62 into a convenient receptacle, and may be packed as an inferior grade. Or, on the other hand, unusually good apples may be selected and placed on the conveyor 60, the fine apples thus being divided into two groups, one of which is placed on the conveyor 58 to be used as a top layer in heading the crates or barrels, while the other is placed on the conveyor 60 to be packed as an extra fine grade. It will be seen that the conveyors are so arranged that great flexibility of operation is possible. Different apple packers may use these conveyors 37, 58 and 60 in different ways, each packer deciding for himself what grade or class of apples is to be placed on each conveyor, and what use will be made of each grade or class.

The apples which are not removed manually from the inspection conveyor 45 are discharged at the end of this conveyor adjacent the sprockets 48. Ordinarily, the apples manually removed would be but a small part of the total apples carried by the conveyor, so that the great majority of the apples would remain on the conveyor until discharged at the end thereof.

It has been found in practice that the discharge of the apples is facilitated if the rotation of the rollers 45 is stopped adjacent the discharge point, or if the rollers are rotated slightly in a reverse direction. Referring now to Fig. 9, a roller 65^a is shown mounted on the same shaft with the sprockets 48, this roller being of such diameter that the conveyor rollers 45 will contact therewith when the links 46 move around on the sprockets 48. If it is preferred simply to stop the rotation of the rollers 45, the roller 65 may be fixed to the sprockets 48 so as to rotate therewith. Obviously, when the rollers 45 run off of the end of the member 50 which caused their rotation and come into contact with the periphery of the roller 65 which is moving at the same speed as the bodily movement of the rollers 45, the rotation of these rollers will cease.

On the other hand, if it is desired to rotate the rollers 45 in a reverse direction at the discharge point, which is found in some instances to produce a better discharging action, then instead of fixing the roller 65 to the sprockets 48, the roller 65 may be driven in the same direction as the sprockets and slightly faster than these sprockets. Consequently, when the rollers 45 come into con-

tact with the periphery of the rollers 65, they will be rotated clockwise or in a reverse direction compared to the counter-clockwise rotation caused by the member 50.

After the rollers 45 have passed partly around the sprockets 48, they move rightwardly back to the other sprockets 47 along the return or lower stretch of the conveyor, this stretch being supported by the shelf or plate 66 (Fig. 9) which may be covered if desired by a layer 67 of leather, rubber, or fabric in order to deaden the noise which would be caused by the rollers 45 rolling along the member 66.

The apples discharged from the inspection conveyor fall onto an inclined member 70 (Fig. 9) down which they roll or slide onto a sorting conveyor 71, which is preferably constructed of rings such as are shown in Figs. 10 and 11, in a manner similar to the conveyor 24. The diameters of the rings in the conveyor 71 are slightly larger than the diameters of the rings forming the conveyor 24, so that apples slightly larger than those dropped through the conveyor 24 will drop through the perforations in the conveyor 71 and will thus be separated from the still larger apples which will remain on the conveyor. This conveyor 71 travels over polygonal rollers 72 and 73 (Figs. 1, 3, 5 and 9) which are similar to the polygonal rollers 30 and 31 of the conveyor 24, but which have slightly larger faces or sides, since the rings 25 of the conveyor 71 are slightly larger than those of the conveyor 24. The conveyor 71, like the conveyor 24, is inclined slightly upwardly so that apples which do not immediately become seated in the perforations will roll back toward the lower end of the conveyor until they find vacant perforations through which they may drop or in which they may be seated if they are of too large a diameter to go through the perforations.

The inclined member 70, mentioned above, is preferably made of resilient material, such as a sheet of rubber or the like. It is supported at its upper edge, as shown in Fig. 9, and extends downwardly and forwardly almost into contact with the conveyor 71 when this conveyor is in its lowest position. As the conveyor rises slightly due to the rotation of the polygonal rollers over which it runs, it may come into contact with and lift the free edge of this resilient member 70. The resilient construction also has another advantage, in that it provides a somewhat soft and flexible member for the articles to fall upon when they are discharged from the preceding conveyor, and thus greatly lessens the chance of bruising fruit or breaking fragile articles being handled by the apparatus.

The apples falling through the perforations of the conveyor 71 form a small grade of packing apples and drop onto a transverse

or lateral conveyor arranged between the upper and lower stretches of the conveyor 71 as illustrated for example in Fig. 5. This lateral conveyor runs approximately at right angles to the direction of travel of the conveyor 71, and comprises a belt 75 of canvas or the like which is arranged to run over a roller 76 at one end and another roller (not shown) at the other end. This conveyor 75 is driven in a direction to transport the apples which fall through the perforations of the conveyor 71 laterally and to discharge them onto a packing table 77 (Fig. 7) having a vertical partition 78 to separate the apples roughly into two groups, the packing table 77 being slightly inclined so that the apples will roll down toward a pair of gates or doors 79 which may be opened when it is desired to discharge the apples from the packing table into suitable packing crates or barrels.

The apples which are too large to go through the perforations of the conveyor 71 are discharged at the end of this conveyor 25 onto an inclined resilient member similar to the member 70, from which they pass to a second conveyor 80 running over polygonal rollers 81 and 82. This conveyor 80 is similar to the conveyor 71 except that the diameters of the perforations or openings therein are still larger than those of the conveyor 71. Thus apples of a slightly larger size than those dropping through the conveyor 71 will drop through the conveyor 80 and will fall 30 onto a lateral conveyor comprising a belt 84 similar to the belt 75, and running over rollers 85 and 86 in a manner similar to the conveyor 75. The apples received by the conveyor 84 form an intermediate packing 40 grade of apples larger than the grade dropping onto the conveyor 75, but smaller than the still larger apples which are too large to drop through the perforations of the sorting conveyor 80. The conveyor 84 discharges 45 these apples onto a slightly inclined packing table 87 (Figs. 6 and 7) which is similar to the packing table 77 and which has a similar dividing partition 88 and discharge gates 89. The apples on these packing tables 77 and 87 may be packed or otherwise disposed of in any suitable way. Furthermore, operators may be stationed alongside the conveyors 75 and 84 to inspect the apples as they move along on these conveyors, and may 55 eliminate any undesirable or imperfect apples which may have escaped the inspectors stationed adjacent the inspection conveyor 45.

As many separating conveyors as desired 60 may be employed, each similar to the conveyors 71 and 80 except that each succeeding conveyor would have openings or perforations of slightly larger diameter than the preceding one. In the present embodiment, 65 the two conveyors 71 and 80 are found to be

sufficient. Accordingly, the conveyor 80 is arranged to discharge the apples which do not fall through the perforations onto an inclined plate 90 (Fig. 4) down which they roll or slide onto a conveyor belt 91 of canvas or the like which runs around rollers 92 and 93 and is arranged to carry the apples forwardly and slightly downwardly to a packing table 94. This table 94, as shown in Fig. 7, is somewhat Y-shaped, being divided into two parts by a V-shaped partition 95. The apples transported by the conveyor 91 are deflected to one side or the other by the partition 95 and thus accumulate in two groups at the end of the Y-shaped packing table 94. These apples, since they are the ones which did not drop through the holes in any of the conveyors, form the largest grade or size of the sizes automatically separated by the mechanism, and are exceeded in size only by the hand picked apples selected by the operators from the inspection conveyor 45 and manually placed by them on the conveyor 58 or other appropriate conveyor.

According to the present invention, the chute 59 which receives the extra fine apples from the conveyor 58, is arranged to discharge them into the space between the V-shaped partition 95 of the packing table, this space being indicated by the numeral 96 in Fig. 7. Thus these fine apples are placed between the two groups of large sized apples fed to the table by the conveyor 91, so that they are in the most convenient position for use by the packers who are packing the apples from the packing table 94. Ordinarily, the crate or barrel would be filled nearly to the top with apples from the table 94, and then the extra fine apples from the space 96 would be used as a top layer, ordinarily referred to as headers. If preferred, however, the fine apples from the space 96 could be packed by themselves as a separate grade instead of being used as headers for the apples on the packing table 94. It will be seen, therefore, that this placing of the extra fine apples in a space between two groups of other apples is a most convenient arrangement, permitting the extra fine apples to be packed either by themselves or in conjunction with the other apples.

As the extra fine apples come down the chute 59, their velocity is checked by a strip 100 (Fig. 4) of resilient material such as rubber or felt, which is fixed at its upper edge to a cross bar 101 extending across the chute. The fruit hits this strip 100 and thrusts it momentarily upwardly so that the fruit passes beneath the strip, but in so doing, the velocity of the fruit is greatly reduced, being slowed down to such an extent that there is no danger of bruising the fruit by falling violently onto the table 96.

It may be noted at this point that great

care has been taken throughout the entire apparatus to prevent rough handling or bruising of the fruit, and especially of the better or larger grades of fruit. Wherever possible, inclined chutes or runways have been used in place of vertical drops, and in some instances (such as the plate 70) the inclined members have been made of rubber or the like to prevent still further the possibility of damage to delicate fruit. It is found that the most delicate fruit, such as peaches, may be handled easily by this apparatus without any substantial amount of damage.

Preferably at least one of the rollers of each of the conveyors is adjustably mounted, so that the tension of each conveyor may be varied at will. An adjusting screw 49 for the sprockets 47 of the inspection conveyor is shown in Fig. 2. A similar adjusting screw 20 for the roller 92 of the conveyor 91 is illustrated in Fig. 3, and similar arrangements may be used for all the other conveyors.

Various parts of the apparatus may be driven in any suitable way. For instance, as illustrated in Figs. 1 and 2, a motor 105 may be provided to drive a belt 106 which drives a large pulley 107 on a shaft 108. This shaft, in turn, carries a smaller pulley 109 around which runs a belt 110 which drives another large pulley 111 on a shaft 112 (Figs. 1, 3 and 5). A sprocket 113 on the shaft 112 drives the chain 114 extending rearwardly to a sprocket 115 (Figs. 1 and 2) from which is driven, by another chain 116, the roller 22 of the first conveyor 20 to which the fruit is originally supplied.

The shaft 112 is extended to the opposite side of the machine from that shown in Figs. 1 and 3, and is provided at this opposite side with a sprocket 120 (Fig. 5) driving a chain 121 which drives another sprocket 122 fixed to the shaft 123 on which the sprockets 48 of the inspection conveyor 45 run. In this way the inspection conveyor is driven. The shaft 123 also carries a sprocket 124 driving a chain 125 which extends forwardly as indicated in Fig. 5 and drives the polygonal rollers 73 and 82 of the conveyors 71 and 80 respectively.

Referring now to Fig. 3, the polygonal roller 73 which is driven in the manner just described has a sprocket 130 fixed to it over which runs a chain 131 driving a sprocket 132 on a shaft 133. Another sprocket on this shaft 133 drives the chain 134 which is connected to the roller 39, thus driving the conveyor 37. This shaft 133 also has a bevel gear 136 as shown in Fig. 5, which meshes with another bevel gear 137 on a short shaft 138 journaled on the outer side of the posts 139, 140 and 141. This shaft 138 carries a sprocket 142 which, as shown in Fig. 6, drives the chain 143 which in turn drives another chain 144 which rotates the roller 86 at the delivery end of the conveyor 84 and the cor-

responding roller at the delivery end of the conveyor 75.

Beyond the post 141, the shaft 138 has a spur gear 146 which meshes with another spur gear 147 as shown in Fig. 6 (the gear 147 being directly behind the gear 146 when viewed as in Fig. 5), which gear 147 is on a shaft 148 journaled on the inner side of the posts 141 and 149. At the end of this shaft 148 is a gear 150 meshing with another gear 151 on a shaft 152 which drives the elevator 42.

In addition to driving the chain 134 and the bevel gear 137, the shaft 133 also drives a chain 155 (Figs. 1, 4 and 5) which in turn drives a shaft 156 which drives another chain 157 which is connected to the roller 57, thus operating the belt 55 forming the two conveyors 58 and 60. The shaft 156 also drives another chain 158 which rotates the roller 93 of the conveyor 91.

Many of the conveyors used in this apparatus may be formed of belts of canvas or other fabric. One form of belt joint for such conveyors is shown in Figs. 12 and 13. A portion 160 of a belt has members 161 of wire or the like attached thereto in such manner as to form eyes extending slightly beyond the end of the belt. The other end portion 162 of the belt has similar members 163 likewise forming eyes, staggered relative to the members 161. When the belt has been placed in position over its rollers, a rod 164 is then slipped through the eyes of the two sets of members 161 and 163, thus joining the two ends of the belt firmly together and forming a sort of hinge connection.

It is found in practice that with constant use the edge of the belt is apt to fray slightly, so that one of the members 161 or 163 which is closest to the edge will pull out, and then as the fraying continues the next member will pull out, and so on. To prevent this, and to provide a belt joint which is of great durability and which can stand up well under hard usage, a guard member is used to prevent fraying of the edges of the belt at the joint. This guard member may comprise, for example, a piece 165 of leather or other tough material which is folded over the edge of the belt as shown in Fig. 13, and which is held in place by means such as the rivets 166. This guard member may be of substantially circular shape before being applied to the belt, so that the portion thereof on each side of the belt after it is applied is substantially semi-circular, as shown in Fig. 12, although other shapes may be used if preferred. Not only is fraying of the joint prevented by this arrangement, but also the guard member strengthens the joint since it is attached firmly by the rivets to both ends of the belt, and thus acts as a splice for the belt.

The operation of the apparatus has been described more or less in detail in connection

with the particular description of the parts of the mechanism but a brief resume will be given here for convenience, apples being chosen for purposes of illustration and not in a limiting sense.

The apples as they arrive in the packing house are placed upon the conveyor 20 and are transported thereby onto the first separating conveyor 24, which allows the apples of comparatively small size to drop through this conveyor and down the chutes 35 and 36 onto the conveying belt 37. The sizes of the perforations or openings in the conveyor 24 are such that only comparatively small apples, too small for ordinary packing purposes, will drop through these openings. These small apples, after being deposited upon the conveyor 37, are delivered by this conveyor to the elevator 42 and discharged from the upper end of this elevator into a suitable receptacle such as a barrel, or to another conveyor, to be used to make cider or any other desired product.

The larger apples, which do not pass through the perforations in the conveyor 24, are discharged at the end of this conveyor onto the incline 32, from which they pass to the inspection conveyor comprising the rollers 45. The apples lie in the crevices or troughs between these rollers, and as the rollers turn during the motion of the conveyor, the apples are rolled over and over so that substantially all parts thereof may be seen easily by the operators stationed beside the conveyor for inspection purposes. These operators select those apples which are for any reason so defective that they cannot be packed, and drop such defective apples into the chutes 65 conveniently accessible to the operators, the apples falling down the chute to the conveyor 37 and being mingled with the smaller size apples delivered to this conveyor from the separating conveyor 24, so that these defective apples may be made into cider or other desired products.

The operators stationed beside the inspection conveyor 45 not only eliminate defective apples, but also watch out for exceptionally fine apples, such as those of unusually large size or of unusually good quality, and manually remove these fine apples from the conveyor 45, placing them by hand on the conveyor 58 by which they are transported to the chute 59. These extra fine apples roll or slide down the chute 59 past the resilient member 100 which slows down the apples so that they will not become bruised when they emerge from the chute 59 onto the space 96 of the packing table. These apples may be packed by themselves, or they may be used as a top layer on crates or barrels of other apples.

In addition to selecting from the inspection conveyor 45 the defective apples to be placed in the chutes 65 and the extra fine

apples to be placed upon the conveyor 55, the operators stationed beside the inspection conveyor may also select other apples according to any desired criterion, and place them upon the conveyor 60. For instance, this third group of apples may be apples which are slightly defective, but which are fit to be packed as an inferior grade rather than to be used simply for cider or other apple products. The apples placed upon this conveyor 60 are deflected laterally by the deflector 61 and go down the chute 62 to any suitable receptacle.

The remaining apples upon the inspection conveyor 45, which were not manually removed therefrom by the operators, are discharged from this conveyor onto the resilient plate 70 which is sufficiently soft and flexible so that apples or even more delicate fruits are not bruised when discharged from the conveyor, and from this plate 70 they pass to the sorting conveyor 71, having openings therein of slightly larger diameter than the openings in the preliminary sorting conveyor 24. The apples which drop through these openings are transported laterally by the conveyor 75 to a packing table 77, where they are packed as a commercial grade of apples.

The larger apples, which did not pass through the openings of the conveyor 71, are delivered by this conveyor to the next sorting conveyor 80, which has perforations or openings of still larger diameter. Accordingly, part of the apples will drop through this conveyor 80 onto the conveyor 84, by which they will be transported laterally to the packing table 87, where they may be packed as another commercial grade of apples, somewhat larger than those packed from the table 77.

The apples which do not drop through the conveyor 80 and which are accordingly discharged from this conveyor onto the conveyor 91 are, of course, still larger than the apples which find their way to the packing table 87. These larger apples are carried by the conveyor 91 to the spaces 94 on another packing table, these spaces being on both sides of the space 96 to which the extra fine apples were delivered by the conveyor 58. Accordingly, these extra fine apples in the space 96 are conveniently accessible to the packers packing the apples from the spaces 94, so that they may be used as headers or a top layer for the latter apples, although they may be packed separately if preferred.

If it is desired to separate the apples or other fruit into a greater number of groups according to size, additional sorting conveyors may be inserted in the apparatus between the conveyor 80 and the final delivery belt 91. The diameters of the openings in the various conveyors may be chosen at will to suit the requirements of the packer, each

conveyor having openings slightly larger, of course, than those of the preceding conveyor.

The novel guard member 165 at the joint of each of the belt conveyors prevents fraying of such conveyors and enables them to stand up satisfactorily under hard usage for a comparatively long period of time.

The apparatus may be used satisfactorily for a wide variety of fruits, vegetables, and the like, apples being mentioned only by way of example. As has been pointed out heretofore, the various parts of the apparatus are so designed that the fruit is handled gently and even the most delicate fruits such as peaches may be sorted satisfactorily by this apparatus without any substantial amount of bruises. The apparatus may also be used effectively for sorting various fragile articles such as glass globes and the like, and obviously could be employed for articles which are not fragile or delicate. The shapes of the perforations or openings in the various sorting conveyors would be varied to suit the articles with which the apparatus is to be used.

It will be seen that apparatus of great flexibility has been provided, since it may be used not only for many different kinds of articles, but when used for sorting any one article, it may be employed in a number of different ways. For instance, each user may decide for himself what class or grade of articles is to be placed upon each of the conveyors 37, 58 and 60, and each user may define his own criteria for the selection of these various classes or grades.

While one embodiment of the invention has been disclosed, it is to be understood that the inventive idea may be carried out in a number of ways. This application is therefore not to be limited to the precise details shown, but is intended to cover all variations and modifications thereof falling within the spirit of the invention or the scope of the appended claims.

I claim as my invention:

1. In a sorting apparatus, the combination with a series of rollers, of mechanism for moving said rollers bodily toward a discharge point, means for causing rotation of certain of said rollers in one direction to turn articles resting upon said rollers to expose different portions of such articles to view for purposes of inspection, and means for causing rotation of said rollers in the opposite direction at said discharge point.

2. In a fruit sorting machine for the continuous progressive grading of fruit, the combination with a frame, a device for feeding bulk fruit to one end thereof, a distributing table at the other end having diverging partitions separating it into channels for selective distribution to receptacles and comprising a central channel and lateral channels, and a laterally arranged distributing

table having a chute leading thereto from an intermediate portion of the machine, of a cull eliminator adjacent to the feeding device, a moving inspection table progressively adjacent to the latter, a grading apron progressively adjacent to said table and adapted to deliver into the lateral chute, a conveyor progressively adjacent to said apron and running to the lateral channels of the end table in the plane thereof, and a longitudinally extending conveyor above the instrumentalities aforesaid having a chute delivering into the central channel of the end distributing table, said last mentioned conveyor and the inspection table being jointly accessible to the same operator.

3. In a fruit sorting machine for the continuous progressive grading of fruit, the combination with a frame, a device for feeding bulk fruit to one end thereof, a distributing table at the other end having diverging partitions separating it into channels for selective distribution to receptacles and comprising a central channel and lateral channels, and a laterally arranged distributing table having a chute leading thereto from an intermediate portion of the machine, of a cull eliminator adjacent to the feeding device, a moving inspection table progressively adjacent to the latter, a grading apron progressively adjacent to said table and adapted to deliver into the lateral chute, a conveyor progressively adjacent to said apron and running to the lateral channels of the end table in the plane thereof, a longitudinally extending conveyor above the instrumentalities aforesaid having an upper reach provided with a chute delivering into the central channel of the end distributing table and a lower reach provided with an ejector delivering laterally at the first mentioned end of the machine, both reaches of said last mentioned conveyor and the inspection table being jointly accessible to the same operator.

4. In a fruit sorting machine for the continuous progressive grading of fruit, the combination with a frame, a device for feeding bulk fruit to one end thereof, a distributing table at the other end comprising a central channel and lateral channels, and a laterally arranged distributing table having a chute leading thereto from an intermediate portion of the machine, of a cull eliminator adjacent to the feeding device, a cull removing conveyor extending longitudinally beneath the machine in cooperation with the cull eliminator, a moving inspection table progressively adjacent to the latter, a grading apron progressively adjacent to said table and adapted to deliver into the lateral chute, and a conveyor progressively adjacent to said apron and running to the end table, the said cull conveyor being provided with chutes adjacent to the inspection table jointly accessible therewith to the same operator.

WILLIS A. TRECOTT.
